CLAIM

The ornamental design for a testing device, as shown and described.

DESCRIPTION

FIG. 1 is a top perspective view a testing device;
 FIG. 2 is a top view of the testing device;
 FIG. 3 is a bottom view of the testing device;
 FIG. 4 is a first end view of the testing device;
 FIG. 5 is a second end view of the testing device;
 FIG. 6 is a first side view of the testing device;
 FIG. 7 is a second side view of the testing device;
 FIG. 8 is a bottom perspective view of the testing device;
 and,
 FIG. 9 is a top perspective exploded view of the testing device.
 The broken lines in the figures depict portions of the testing device that form no part of the claimed design.
